UNITED STATES PATENT OFFICE.

ALDUS A. BRACKBILL, OF GREENLAND, PENNSYLVANIA.

WHIFFLETREE-HOOK.

SPECIFICATION forming part of Letters Patent No. 352,295, dated November 9, 1886.

Application filed July 17, 1886. Serial No. 208,335. (No model.)

To all whom it may concern:

Be it known that I, ALDUS A. BRACKBILL, a citizen of the United States, residing at Greenland, in the county of Lancaster and State 5 of Pennsylvania, have invented certain new and useful Improvements in Frizzen-Hooks and Expansion-Links for Double and Single Trees; and I do hereby declare the following to be a full, clear, and exact description of the 10 invention, such as will enable others skilled in the art to which it appertains to make and use the same.

Frizzen-hooks as heretofore made have been solid oblong straps with the hook attached, the 15 link used being the ordinary chain-link, it being necessary in this case to heat the frizzen to expand the same in order to get it on the vehicle-furniture.

The object of my invention is to provide, as 20 a new article of manufacture, a frieze iron or strap that can be made of malleable cast iron or steel for use on single or double trees, and in combination with the frizzen to furnish an expansion-link which shall be easily placed 25 in position on the frizzen, and will expand or contract, according to the strain exerted by the team, and relieve the sudden jar which would occur by the use of the solid link. I attain these objects by the mechanism illustrated 30 in the accompanying drawings, similar letters referring to similar parts throughout the several views.

Figure 1 is a side elevation of the frizzen-hook and expansion-link; Fig. 2, a top elevation of the same. Figs. 3, 4, and 5 show the expansion-link apart. Fig. 6 is a top view of the expansion-link, through the line A A in Fig. 1. Fig. 7 is a top view of Fig. 3.

In the side elevation, Fig. 1, B represents 40 the body of the single-tree; C, the body of the frizzen; D, the hook attached to the frizzen; E, the spring which is held in position by the bolt F, which serves the double purpose of holding this spring in position and clamping the body 45 of the frizzen C fast to the single-tree B. G in this figure represents the top hook of the expansion-link; H, the spring; I, the bottom hook of the same.

Figs. 3, 4, and 5 show the expansion-link 50 apart. G, of Fig. 3, represents the top set of spring-hooks; H, in Fig. 4, the spiral spring; I, of Fig. 5, the bottom set of spring-hooks.

Fig. 6 is a top view of the expansion link through the line A A of Fig. 1. It will be seen that both the top hooks, G, and the bottom hooks, I, are composed each of four hooks, which, when in position on spring and together, would show a transparent perspective, as represented by Fig. 6, through the line A A, Fig. 1.

Fig. 7 is a top view of the hooks, G, in Fig. 6, showing a transparent perspective of this part of the expansion-link when they are apart.

Having thus described these improvements, the manner of working them is as follows: The end of the single-tree B having been cut 55 somewhere near the size, the bolt F is backed out of the frizzen C, so as to allow this frizzen to spring apart at the joint f f. By this means the frizzen-strap C is easily forced on the end of the single-tree B, the spring E being then 60 brought in the proper position to bear against the hook D at d. The tap-bolt, F, is drawn tight, which clamps the strap C fast to the end of the single-tree B, and presses the projecting points a a a a fast into the wood, which 65 effectively prevents any tendency of the strap to turn on the same. Although I show projecting points a a a a on the inner sides of the frieze-iron, one central V-shaped rib, nearly 70 across the entire width of the strap, might be 75 cast with corrugated saw-teeth in its edge. The advantage of this rib over the teeth would be that it would not be necessary to open the strap so wide to drive it on the end of the single-tree, for the groove made by the rib cutting into the wood would be entirely filled by it, and the tendency to fracture the malleable iron by springing it open consequently lessened.

The object of the spring E, where it presses 85 against the hook D at d, is to allow the expansion-spring to be slipped in and out, as the occasion may require, and also to form a hardened-steel washer for the head of the tap-bolt, F, to screw down on. The front end of the spring 90 E, where it presses against the hook at d, is rounded off, so as to form a projection on the inside to slip the link through.

The expansion-link, which is shown apart in Figs. 3, 4, and 5, when put together and the 100 eye of the upper hooks, G, pushed past the spring E at d on the frizzen-hook D, which is attached to the single-tree B, the whole combination is together and ready for use. When

the trace chains or hooks are attached in the eye *e* of the lower hooks, *I*, and the team pulls in the direction of the arrow *o*, it will be seen that the spring *H* is compressed by means of 5 the hooks *G* and *I* pulling on the ends of the spring *H* from opposite directions—the ends of hooks *I* in the direction of the arrow *i*, and the ends of hooks *G* in the direction of the arrow *g*—accomplishing the desired object of 10 forming an expansion-link which will have the tendency to relieve the starting-strain of the team, which would be encountered by the use of a solid link.

Having thus described my invention, what 15 I claim, and desire to secure by Letters Patent, is—

1. As a new article of manufacture from malleable cast iron or steel, the frieze-strap *C*, al-

most entirely around the single-tree *B*, with the hook *D* attached, and the tap-bolt *F*, which 20 screws into the body of the strap *C*, so as to require no loose nut, and holds the spring *E* in position, said spring also serving as a hardened-steel washer for the head of the bolt *F*, substantially as set forth and described. 25

2. In combination with the frieze-iron *C*, the expansion-link composed of the upper spring-hooks, *G*, and the lower sprinck-hooks, *I*, with the spring *H*, when constructed as shown, and for the purpose described. 30

In testimony whereof I affix my signature in presence of two witnesses.

ALDUS A. BRACKBILL.
